MULTIPLE PACKER

Ferdinand J. Spang, Butler, Pa.

Application July 3, 1936, Serial No. 88,793

12 Claims. (Cl. 166—10)

This invention relates to the recovery of oil from oil bearing strata by a re-pressuring process, and more particularly to a method and apparatus for conditioning the pressure wells to secure a more uniform flow of the re-pressuring fluid through the various strata and thereby secure a greater recovery of oil from such strata than has heretofore been possible with previous methods and apparatus.

10 In the production of oil, a well is drilled through the various strata making up the oil bearing formations. On the tapping of the strata, the gas, which is usually found in the strata, either intermingled with or behind the oil, in a highly compressed state, expands and forces the oil into the well and thence to the surface. As this gas expands, the pressure declines to such an extent that it is insufficient to cause oil to flow from the well and it becomes necessary to raise the oil by either pumping the well or by other mechanical means. Eventually the pressure of the gas drops below the point necessary to force the oil out of the various strata and into the well and consequently the well has to be abandoned even 25 though a large percentage of oil remains within the pores of the formation.

It has become a common practice in recent years to re-drill territory that has previously been abandoned because of primary exhaustion 30 and the oil contained in the pores recovered by re-pressuring the strata. In the re-pressuring process, at least two wells are drilled, one of which is termed the producing well and the other is utilized as a pressure well, into which 35 air, gas, or water is forced under pressure and thence into the oil bearing strata to move the oil in that strata into the producing well.

During the drilling of the pressure wells, a core is removed from which the formation, through 40 which the well is drilled, can be readily determined as well as the oil content of the various sand horizons, the separation of such sands from one another and the porosity and permeability of these sands.

45 The pressure well or wells is spaced from the producing well in accordance with the porosity of the strata encountered based upon data obtained from a study of the cores taken from the wells. Such spacing is usually the result of the average 50 porosity of the various strata and consequently the re-pressuring fluid passes through the open or low grained sand horizons much quicker than it does through the close grain sand horizons having a lesser permeability. Therefore, the re- 55 pressuring, as heretofore practiced, did not and

could not result in either a complete or uniform recovery from the various oil bearing strata where all of the strata were subjected to the same pressure. Further, it is not uncommon for the pressuring fluid to bypass the oil through 5 the looser sands or strata into the producing well before the fluid had penetrated the tighter or less permeable sands. It is, therefore, apparent that in order to recover substantially all of the oil contained in the oil bearing strata it is 10 necessary to make some separation of the strata at the points where natural pronounced permeability changes occur in the sands in order that the rate of input of the re-pressuring fluid may be regulated at the surface and the oil movement 15 within the strata controlled.

It is an object of the present invention to provide for the selective regional regulation of pressuring fluid into the various sands to obtain the maximum recovery of oil from each sand and, 20 hence, materially increase the recovery from all the oil bearing strata.

My invention may also be used to great advantage in effecting the proper control of oil recovery from newly drilled oil fields whereby it is 25 possible to avoid the depleting of the more highly permeable strata before the lesser permeable strata are exhausted, since the depletion of the oil in the more permeable sands frequently results in a flooding of the well due to the passage 30 of water through the depleted permeable strata, and the consequent loss of the well. This flooding of the wells can be prevented to some extent by the use of my method and apparatus, since the less permeable strata can be segregated from 35 the more permeable strata and subjected to pressure, whereby the recovery from such sands can be made to more nearly approach the recovery from the permeable sands and all of the sands 40 are exhausted at substantially the same rate.

Another object of my invention is to provide 45 means for separating the various oil bearing strata and to provide means for controlling both the pressure and volume of the flow of pressuring fluid to each sand. To my knowledge, a series of separate packer units have been used heretofore to separate the various oil bearing strata in which each packer was run on an independent and separate string of tubing or casing, one string being nested within the other. Such system was not only exceedingly expensive, but the results obtained by a series of independent packers were generally unsatisfactory 50 since there was no way of testing the perfection 55

of the packing of the different packers or to determine whether each packer was fully set.

A further object of my invention is to provide a multiple packer by which all of the various oil bearing strata in a pressure well may be separated whereby the input of the re-pressuring fluid into the well and thence into the various strata is independently controlled.

A still further object is to provide a packer in which each of the packing units may be actuated and/or set and tested in consecutive order and in which each unit is provided with a separate means for introducing a re-pressuring fluid into the strata separated by the elements carried by my improved multiple packer.

A still further object is to provide means for separating the various oil bearing strata in which each unit of the packing elements may be separately actuated or set by the entire force of the load applied from above and in which means are provided for locking each of the packing units in its set or packed position.

These and other objects which will be herein-after made apparent to those skilled in this particular art are accomplished by means of this invention, one embodiment of which is described in the following specification and illustrated in the accompanying drawings, wherein:

Figure 1 is a diagrammatic view of an oil well showing the various oil bearing strata separated by means of a multiple packer made in accordance with the present invention, to permit selective re-pressuring of the several productive strata and also the means for introducing the re-pressuring fluid into each oil bearing stratum;

Fig. 2 is an enlarged vertical section of one of the intermediate packers employed;

Fig. 2a is an enlarged vertical section of the lowermost packer employed with the actuating means for successively setting the packer in the position it occupies when the packer is being lowered into a well;

Fig. 3 is an enlarged sectional view of one unit of my multiple packer with the packer element in its set or packed position;

Fig. 4 is an enlarged view illustrating the means for setting the packer;

Fig. 5 is a view in perspective of a clutch for holding the units of the packer together in the string and for holding the packer elements in their expanded position after the units of the packer have been set;

Fig. 6 is an enlarged sectional view illustrating the improved type of coupling used to join the body of the packer units to the tubing or casing and showing the means for maintaining the re-pressuring tubes in fixed position;

Fig. 7 is an enlarged sectional view on line VII-VII of Fig. 1;

Fig. 8 is an enlarged view in perspective of the top of my improved packer showing the re-pressuring tubes and the means for setting the packer; and

Fig. 9 is an enlarged view in perspective of the casing head illustrated in Fig. 1.

Referring to Fig. 1 of the drawings, F represents a formation typical of the character usually found in oil bearing localities, and W a pressure well which is one of a series that have been drilled through the formation F, and arranged in a suitable pattern for repressuring such as a 5, 7, or 9 spot pattern. When water is used as the re-pressuring fluid, the wells forming the periphery of the pattern are utilized as the pressure wells and the oil is removed from the central well

or wells of the pattern, but when a gas is used to re-pressure the oil bearing strata this arrangement is generally reversed and the re-pressuring gas is introduced into the well or wells in the center of the pattern and the oil is recovered from the peripherally arranged wells.

The formation F comprises an overlying structure L, an oil producing strata composed of a series of individual stratum S1, S2, S3, S4, S5, naturally separated from each other by a series of non-porous structures R1, R2, R3, R4, and a cap rock M, which separates the overlying structure L from the oil producing strata.

During the drilling of the well W and the other wells making up the re-pressuring pattern of which W is a part, cores of the formation below the cap rock M were taken and from these cores the porosity, permeability, and oil content of the various oil sands S1, S2, S3, S4, S5 are determined, and for convenience in describing my invention it will be assumed that these cores show that each of the sand horizons S1, S3, S4 and S5 are productive, but that each differs both in permeability and porosity and that the sand S2 is a barren or exhausted sand. Consequently in order to secure uniform flow of the re-pressuring fluid through each of the stratum S1, S3, S4, and S5 to move the oil therein at a substantially uniform rate toward the output well and to prevent the admission of the re-pressuring fluid or gas to the barren sand S2 it is apparent that each stratum must be separated from the other, and that the flow of re-pressuring fluid into the sands S1, S3, S4 and S5 must be controlled in accordance with the variables in the permeability and porosity of each sand by varying the pressure and volume of the fluid introduced into each such productive sand.

In order to separate and segregate the sands S1, S2, S3, S4 and S5 at their points of natural separation R1, R2, R3 and R4 and from the overlying structure L and to control the amount of gas or fluid admitted under pressure to each such sand so that the flow of re-pressuring fluid or gas will be uniform throughout the various strata, I introduce into the well W a string of tubing or casing T having a series of telescoping units or sections P1, P2, P3, P4 and P5 therein which are spaced vertically in accordance with the measurements determined from an analysis of the core removed from the well W. Each of the units P1, P2, P3, P4 and P5 carries an expandible element E and these units are so spaced vertically that on telescopic movement of the units, the elements E will be expanded and pressed against the well wall at the points M, R1, R2, R3 and R4 and thus separate the various sands S1, S2, S3, S4 and S5 from each other.

Each of the telescoping units or sections P1, P2, P3, P4 and P5 comprises a top coupling member 10 threaded to the lower end of a section of casing or tubing T and a body member 11 which is, in turn, threaded to the coupling 10 and carries the expandible packing element E. The upper end of the element E abuts against the coupling 10 and the lower end is supported on an annular coupling 12 which surrounds and is slidable on the body 11.

In order to prevent the coupling 12 from sliding or pulling off the lower end of the body 11 while permitting movement thereof toward the upper coupling 10 to expand the packing element E, an annular clutch element 13 (Figs. 2, 3 and 5) is disposed in a recess 12a in the coupling 12 and is provided with teeth or jaws 13a that are forced

into biting engagement with the body 11 by means of the coacting inclined surfaces 12b—13b on the coupling and clutch respectively, which act as a wedge on the application of a pulling force to the coupling 12, and prevent relative movement between the coupling and the body 11 in a downward direction, but permits such movement in a direction toward the coupling 10 to collapse the tubing and expand the packing element E. Secured to the clutch embracing coupling 12 is a tube or shell 14 which telescopes over the lower end of the body 11 and is threaded at its lower end to a lower coupling 15. Coupling 15 is connected to the upper end of another section of casing or tubing T by means of an annular connecting gland 18 which is threaded into the coupling 15 and abuts against an outwardly projecting shoulder 19 on the casing T. The coupling 15 is of annular or ring shape and has a central aperture 20 for the passage of fluid or tools therethrough as will be more fully explained.

As shown, the packer elements E are held in their extended or unset position while the casing or tubing T is being lowered into the well W, 25 by a series of slips or springs 16, carried by each of the couplings 15, each of which is provided at its upper end with a shoulder 16a, which engages and supports the lower end of the body 11. Each 30 of the slips or body supporting members 16 also has tripping toggle 17 mounted in a slot 16b and supported on a pin 17a which extends through openings or holes in the forked end of the slip 16. Each of the tripping toggles 17 is provided with a cam surface 17b which engages the inner surface 35 of the body 11 whereby on the turning of the toggles about the pins 17a, the slips 16 will be moved inwardly and withdraw the shoulders 16a from beneath the bottom of the body 11. In order 40 to set the packing elements E of the packing units P1, P2, P3, P4 and P5, a rod 25 is positioned in the tubing T with its upper end extending above the telescoping section P1 and its lower end, which terminates in a conical shaped tripping head 26 for turning the toggle 17, seated 45 on the coupling 15 of the lowermost telescoping unit P5. On the upward movement of the rod 25 the conical head 26 successively engages and trips each set of toggles 17 and thereby causes the shoulders 16a to be pulled from beneath the lower ends of the body sections 11 and permit the 50 sections to collapse and expand each of the elements E. To raise or pull the tube 25 upwardly through the tubing T a suitable grappling means, in combination with a socket and a set of jars is run on a suitable line or tube inside the casing 55 T until the grapple engages wickers 27 on the upper end of the rod 25. The rod 25 is then raised vertically until the conical head 26 comes in contact with the tripping toggles 17 on the telescoping unit P5, which are turned, thereby 60 springing the body supporting members 16 inwardly and interrupting the engagement of the shoulders 16a with the bottom of the body member 11, thus allowing it to be moved downwardly 65 inside the shell 14 either by the weight of the tubing above the section or by the addition of weight applied to such tubing. The downward movement of the body section 11, relative to the shell 14, expands the element E due to the pressure between the upper coupling 10 and the clutch embracing coupling 12 and causes it to press 70 against the well wall and the element E is held in its fully expanded position by the gripping or biting action of the clutch 13 on the body 11.

75 After the telescoping unit or section P5 has

been set, that is, the expandible element E has been pressed firmly against the well wall, and the packing has been tested, the rod 25 is raised until it comes into contact with the tripping toggles 17 on the unit P4 and which is then set in the 5 manner heretofore described, and after that setting has been tested, the rod 25 is again raised to set the packing elements E of the units P3, P2 and P1. Thus it is apparent that the setting 10 of the packing units P5, P4, P3, P2, and P1 follow each other in consecutive order and that the lowermost element may be tested, thus tending to show the perfection of its function, before the next expandible element there above it is set. It will also be noted that the entire weight of the 15 casing or tube T and the packing units above any packing unit being set comes to rest on the packing unit being set, and that an external force may be applied through the casing to facilitate 20 the expansion of the packing element and that such expansion will be retained by means of the clutch member 13.

Repressuring fluid is introduced into the sand 25 S5, separated from the sand S4 by the packing unit P5, directly through the casing T, the lowermost section of which above the casing shoe 31 is perforated as at 30, and the casing is supplied with the repressuring fluid through a pipe 32, leading to a suitable source of supply. To deliver 30 repressuring fluid to the sands S1, S3, and S4, a series of tubes 33, 34 and 35 extend through the casing or tubing T and terminate at their lower ends in fluid outlets 36, 37, and 38 in the lower 35 couplings 15 of the packer units P1, P3, and P4, respectively.

To support the tubes 33, 34 and 35 adjacent the side walls of the sections of pipe making up the tubing or casing T, spacers 40 are inserted between adjacent sections of the casing at regularly spaced intervals throughout the length 40 thereof, and inside the coupling 41, joining the adjacent sections together. Each of the spacers 40 (Fig. 6) is provided with a central aperture 42 for the passage of the repressuring gases or fluids and for permitting the passage of the operating apparatus through the tubing and with a series of apertures (as many as may be needed, there being one for each repressuring pipe or tube) through which the repressuring fluid conveying tubes extend. To further support the 50 tubes 33, 34 and 35, the couplings 15 of the packer units P1, P2, P3 are also provided with tube receiving apertures (Fig. 3).

The upward ends of the tubes 32, 33, 34, and 55 35 terminate in a casing head 48 which covers the top of the casing or tubing T. Stuffing boxes 49, 50, and 51 are used to prevent and shut off any leakage around the input tubes 33, 34, and 35, and a central opening, normally covered by a plug 53, is formed therein through which the 60 operating tools, such as the grappling means for setting the packer units P1, P2, P3, P4, and P5, are run into the casing T.

In the running of my improved multiple packer into the well W, a predetermined length of casing T with the perforations 30 therein and the casing shoe 31 in place thereon is attached to the lower coupling 15 of the lowermost telescoping unit P5 of the string, and the unit lowered partially into the well W. Another length of casing 70 T is then attached to the coupling 10 of the unit P5 and the packer unit P4 is then attached to the top of the second length of casing. The tube 35 is then threaded into the outlet opening 75 38 of the lower coupling 15 of the unit P4. This

process is continued until the remaining packing units P3, P2, P1 and input tubes 34 and 33 have been assembled, and the entire apparatus lowered together by means of adding additional lengths of casing T and tubes 33, 34, and 35 until the casing shoe 31 comes to rest on the bottom of the well W.

It will be noted that at this time all of the expansive packing elements E are in their extended or unit positions due to the fact that the body 11 of each packing unit P1, P2, P3, P4, and P5 is resting on the shoulder 16a of the body supporting members 16. The plug 53 is then removed and the grappling means is lowered through the tubing T until it comes in contact with the wickers 21 on the upper end of the rod 25. As the rod 25 is raised the conical head 26 trips the toggles 17 of each of the units and each element E of the units P5, P4, P3, P2, and P1 is set in consecutive order.

It will be apparent from the foregoing description that after the packers have been set it is impossible to remove the apparatus from the well due to the fact that the clutch element 13 bites into and forms a solid connection with the tubing 11 and the shell 14. In order that the tubing 33, 34, and 35 may be independently removed, when occasion demands, a breakable connection or joint 60 is provided in each of the said tubes at a point slightly above the upper telescoping section or unit P1. The joint 60 comprises a finger 61 which is threaded to the lower sections of each of the pipes 33, 34 and 35 and a socket 62 which is secured to the upper section of each pipe and adapted to slide over the finger 61 on the lower section thereof. A yieldable packing member 63 is disposed between the finger 61 and the socket 62 to prevent leakage of the re-pressuring fluid at the connection.

From the foregoing description it is apparent that I have provided a device for conditioning a pressure well in which each of the sands making up the oil bearing strata can be readily separated and segregated from each other by a series of individually set or operated packing elements, all of which are carried by a single string of tubing or casing. Further, with the use of my invention it is possible to introduce re-pressuring fluid into each of the separate sands in predetermined quantities and under predetermined pressures whereby a uniform flow can be maintained through each of these sands and all of them exhausted at substantially the same time.

Further, since the re-pressuring fluid is delivered to each of the sands independently, the amount and pressure of the fluid introduced into each sand can be readily determined from gages and meters disposed at the surface in each re-pressuring tube and adjustments in the volume and pressure can be made daily to insure the complete recovery of all of the oil from the well-bearing strata.

While I have described one embodiment of my invention, it is apparent that certain changes, modifications, additions and omissions may be made therein without departing from the spirit of my invention or the scope of the appended claims.

What I claim as new and desire to secure by Letters Patent is:—

1. In combination with a string of well casing, a series of packers carried by said casing, slips for holding each such packer in extended position, a cam for releasing each said slip, a single means for successively actuating the cams of

each packer whereby said packers are consecutively set, and separate means for delivering fluid pressure to each of said packers.

2. In combination with a string of well casing, a series of connected packers carried by said casing, each having an expansible element, spring slips for holding each such element in extended position, common means for releasing the spring slips of said packers in consecutive order to successively set said packers, means for delivering fluid pressure to each said packer, and means for locking each said expansible element in set position.

3. Apparatus of the character described comprising a series of packers interposed in a single string of tubing of uniform diameter throughout the length of such string, each of said packers including an outer tube, an inner tube slidable in said outer tube, an expansible member carried by said inner tube, members carried by said outer tube for releasably supporting said inner tube, means for releasing said supporting members to permit said inner tube to move relative to said outer tube and set said expansible member, and common means for successively actuating said supporting member releasing means of each packer to consecutively set said packers.

4. A multiple packer for use in a pressure well for separating and supplying fluid pressure to a plurality of productive strata, comprising a series of interconnected packer units each having an outer shell and an inner shell arranged telescopically, an expansible element carried by said inner shell and adapted to be expanded when said shells are collapsed and pressed against the well wall, springs for holding said shells in extended position to maintain said expansible elements in non-expanded position, cams for releasing said springs, common means for successively actuating the cams of said packer units to consecutively expand the elements carried thereby and separate the strata, and means for delivering fluid pressure to predetermined layers of said strata.

5. A multiple packer for use in a pressure well to separate the productive strata thereof, comprising a single string of tubing adapted to be run into said well, a series of vertically spaced packer units interposed in said tubing, each packer unit including a pair of telescoping sections having an expansible element thereon, yieldable members carried by one section of each unit and supporting the other section thereof to hold said sections against relative movement, and an actuator within said tubing adapted to successively engage and move the yieldable members of each unit to a non-supporting position to permit each packer unit to be consecutively set.

6. A multiple packer for use in a pressure well to separate the productive strata thereof, comprising a string of tubing adapted to be run into the well, and having a series of packer units interposed therein at predetermined intervals, each said packer unit including an expansible element and two telescoping tubes arranged to move relative to each other and expand said element, means for releasably supporting said tubes against relative movement, and means within said tubing and movable through said packer units for successively engaging and releasing said tubes supporting means.

7. Apparatus for use in a pressure well to separate the productive strata comprising a string of tubing adapted to be run into said well, and having a series of vertically spaced telescoping

sections therein, clutch means for permitting relative movement at each telescoping section of said tubing in one direction while preventing such movement in the opposite direction, yieldable members for holding each of said telescoping sections in extended position, an expansible element carried by each of said telescoping sections, and means in said tubing and movable through each telescoping section thereof for engaging and moving the yielding members of successive sections to a non-holding position to permit relative telescopic movement in said tubing and expand said expansible elements.

8. Apparatus for use in repressuring the sands of an oil bearing formation comprising in combination a series of packer elements carried by a single string of casing, each of which is provided with separate setting means, means extending through said string of casing and movable in succession through said packers for independently and consecutively operating the setting means of each packer and independent means for discharging fluid pressure into the sands between selected packer elements.

9. Apparatus for use in repressuring the sands of oil bearing formation comprising in combination a series of connected packers, one of which is located at the natural separation between adjacent sands, means for releasably holding each said packer in its inoperative position, releasing cams associated with said holding means, means for independently operating said releasing cams of each said packer to set the same and separate adjacent sands and separate means for delivering fluid pressure to predetermined sands.

10. Apparatus for use in repressuring the sands of an oil bearing formation comprising in combination a series of spaced packer elements mounted at intervals in a single string of tubing of uniform diameter, means extending into said tubing and movable through said packers for consecutively setting each said packer and independent means for delivering fluid pressure to the sands separated by said packers.

11. Apparatus for use in repressuring the

sands of an oil bearing formation comprising in combination a series of packers spaced at intervals in a string of tubing of uniform diameter and located adjacent the natural separations between such sands, each of said packers including 5 telescoping members, a series of yieldable members for releasably holding said telescoping members in an extended position, means for locking said telescoping members against movement in one direction and an expansible element carried 10 by said telescoping members, means for consecutively releasing the yieldable members of each said packer to consecutively collapse said members and expand said elements to separate said sands, and means cooperating with selected 15 packers for delivering fluid pressure to predetermined sands.

12. Apparatus for use in repressuring the several sands of an oil formation having natural separations therebetween, comprising in combination 20 a string of tubing adapted to be lowered into the sands of said formation and having a series of packers therein spaced apart so as to be located adjacent to the natural separations between said sands, each said packer including 25 telescopically arranged members, an expansible element carried by said telescopically arranged members, spring slips for releasably holding said telescopically arranged members in an extended position, cams associated with said spring slips 30 and clutch means carried by one of said telescopically arranged members and adapted to engage the other of said members for preventing relative movement between said members in one direction while permitting such movement in the opposite 35 direction, common means for actuating the cams of each packer to release the spring slips of each said packer in consecutive order to collapse said telescopically arranged members and expand said expansible elements into engagement with said 40 sands to separate the same, and a series of connected tubes cooperating with selected packers for delivering fluid pressure to predetermined sands.

FERDINAND J. SPANG. 45
